[57] **CLAIM**

The ornamental design for a counterweight for an excavator, as shown and described.

DESCRIPTION

FIG. 1 is a rear elevational of a counterweight for an excavator, embodying our new design;
FIG. 2 is a right side elevational view thereof;
FIG. 3 is a left side elevational view thereof;
FIG. 4 is a top plan view thereof;
FIG. 5 is a bottom plan view thereof; and,
FIG. 6 is a top, rear and right side perspective view thereof.
The broken line showing of the excavator is for illustrative purposes only and forms no part of the claimed design.
